UNITED STATES PATENT OFFICE

JOSEPH C. WALTERS, OF PHILADELPHIA, PENNSYLVANIA, ASSIGNOR TO STANDARD BRANDS INCORPORATED, OF NEW YORK, N. Y., A CORPORATION OF DELAWARE

DESIGN FOR A BAG OR SIMILAR ARTICLE

Application filed May 13, 1931. Serial No. 39,823. Term of patent 14 years.

To all whom it may concern:

Be it known that I, JOSEPH C. WALTERS, a citizen of the United States, residing at 105 Daly Street, Philadelphia, Pa., have invented a new, original, and ornamental Design for a Bag or Analogous Article, of which the following is a specification, reference being had to the accompanying drawings, forming part thereof.

The different varieties of linings on the drawings are indicative of contrasting colors.

I claim:

The ornamental design for a bag or analogous article, as shown and described.

JOSEPH C. WALTERS.
